UNITED STATES PATENT OFFICE.

JOHN CRAWFORD AND FREDERICK A. WEAVER, OF DENVER, COLORADO.

EXPANSIBLE BIT.

1,415,317.

Specification of Letters Patent. Patented May 9, 1922.

Application filed May 12, 1920. Serial No. 330,875.

To all whom it may concern:

Be it known that JOHN CRAWFORD and FREDERICK A. WEAVER, citizens of the United States, residing at Denver, in the county of Denver and State of Colorado, have invented certain new and useful Improvements in Expansible Bits; and they do hereby declare the following to be a full, clear, and exact description of the invention, such as will enable others skilled in the art to which it appertains to make and use the same.

This invention relates to tools, and more particularly to expansible bits.

It is one of the objects of the present invention to provide an expansible bit in which there may be provided one or more transversely adjustable cutter blades which are arranged in the end face of the head of the bit in such manner that the cutter or cutters are more firmly supported and may be readily removed, replaced and adjusted to the desired projecting distance, and it is a further object of the invention to provide an improvement in expansible bits in which the removable cutters do all the cutting and the work is divided equally during the rotation of the bit into shavings or chips extending from the lead screw to the circumference of the bit proportionately to the number of cutters which may be employed.

Another object of the invention is to provide, in an expansible bit, a construction which will make possible and practicable the use of cutters which are broad from cutting edge to back but yet comparatively thin, so as to afford great rigidity in the cutter proportional to the amount of steel required.

It is another object of the invention to provide a multiple cutter, expansible bit in which it is necessary to adjust only one of the expansion cutters at an exact position as determined by the diameter of the hole to be bored, and thus enabling the indifferent radial adjustment of the remaining cutters after the position of one of the cutters has been determined as required.

It is another object of the present invention to provide a multiple cutter expansible bit in which the cutters are disposed in symmetrical position with relation to the lead screw of the bit so that cutters operate from the lead screw to the circumference, so that all the cutting is done by the removable, adjustable cutters, which may be readily sharpened out of the tool and in one operation.

It is an important object of the present invention to provide an expansible bit of such construction that a minimum number of relatively separable parts is required; and in this manner to provide a bit of simple construction and in which the entire cutting edge is on the removable cutters.

With these and other objects in view the present invention consists in a bit having a head, the transverse end face of which is provided with means for receiving one or more transversely adjustable and removable cutters, and in which means are provided for securing the cutters in relatively adjusted position firmly and accurately.

There is described in the following specification and illustrated in the accompanying drawing several bits in which the invention is embodied in various forms, and in which drawing:

Figure 1 is a side elevation of a form of the bit showing a pair of symmetrically disposed removable cutters, the shank of the bit being broken away.

Figure 2 is an underneath plan view of Figure 1.

Figure 3 is a side elevation of the bit shown in Figure 2 looking toward the right hand side of the latter.

Figure 4 is a cross section on line 4—4 of Figure 1.

Figure 5 is an underneath plan view of one of the detached cutters.

Figure 6 is an end view of Figure 5 from the right hand end, and

Figure 7 is a transverse section on line 7—7 of Figure 5.

Sheet 2.

Figure 8 is a side elevation of the invention as embodied in a bit having triple cutting blades.

Figure 9 is a bottom plan view of Figure 8.

Figure 10 is a side elevation of Figure 8 looking toward the right side thereof.

Figure 11 is a cross section on line 11—11 of Figure 8.

Sheet 3.

Figure 12 is a side elevation of a bit showing a single cutting blade and in which the head of the bit is arranged to side of the axis of the lead screw and shank of the bit, the latter being broken away.

Figure 13 is a side elevation of the bit shown in Figure 12, and

Figure 14 is a bottom plan view of Figure 12.

Referring to the drawings the shank 2 of the tool is provided with an enlarged head 3 having a flat transverse end and a lead screw 7 extending therefrom. In the flat end of said head is provided one or more transverse cutter receiving slots 5, which may be and preferably are of dovetailed form and 10 arranged tangentially to lead screw 7. Slots 8 are cut in the head 3 dividing said cutter slots 5 longitudinally and extending upwardly in said head a substantial height so that the side walls of said cutter slots may 15 be drawn together as by screws 9 and threaded holes 10 to securely grip the cutters 6. The cutter head 3 may be bell-shaped as illustrated in Figs. 1 and 3 in which event slots 8 will converge toward 20 their upper ends or the head may be cylindrical as illustrated in Figs. 12 and 13, in which event if a plurality of cutters were used, the slots 8 would either converge or be 25 parallel as desired. Further slots D (Figs. 1, 3 and 4) and C (Figs. 8 and 9) are cut in said head to form in conjunction with the beveled edge of cutter 6 shaving escapement slots when multiple cutters are used.

The cutters 6 are of a trapezoidal form in 30 cross section adapted to slide transversely in said dovetail cutter slots 5, and are provided with a cutting edge 6^a and at least one cutter in each tool is provided with a cutting lip 6¹. It will be further noted that the cutters are preferably much broader than they 35 are thick and are adapted to lie with their broad surfaces substantially in the plane of the flat end of the head 3 except for the slight inclination sufficient to drop the cutting edge below the plane of the end face 3 in order to permit the cutting edge to engage 40 and cut the wood and, likewise to raise the noncutting end of the cutter member above the plane of the end face 3 of the head so that such end will clear the wood. In case of three or more cutters the inclination 45 must also be sufficient to permit the cutters to overlap, as indicated at Figs. 8, 9 and 10, and to allow, between the cutters at 50 the overlap, clearance for shavings. With this arrangement it will be noted that the cutting edges will be angularly disposed, as above indicated, relatively to the longitudinal axis of the head and will at the same 55 time lie in vertical planes parallel with said axis but angularly disposed relatively to each other.

It will be noted that this structure affords the maximum rigidity in the cutters 60 with the minimum of tool steel and further provides a wide thin cutting tool which will tend to shave the wood instead of chipping it as is done by the ordinary extension bit.

In the adjustment of the tool the cutters 65 are arranged in the cutter slots 5 with their

cutter edges 6^a extending tangentially from the lead screw 7 to the circumference of the cut. In the multiple cutter forms of this invention the cutter having the lip 6¹ is the only one requiring nicety of adjustment as 70 the other cutters may be more roughly adjusted to a slightly less radius.

In operation the cutters operate from the lead screw to the circumference, and there are no cutting edges integral with the head 75 of the tool thus greatly simplifying the sharpening of the cutting edges, which are entirely removed with the removable cutters and sharpened in one operation.

What we claim is:

1. A bit comprising a head, having a flat end face and a plurality of cutters adjustably mounted in the flat end face of said head, said cutters having their long axes inclined relative to the end face of the head 85 and their cutting edges inclined downward from said face to the outer end of the cutter.

2. A bit comprising a head, with a flat end face, a plurality of cutters having their long axes inclined relative to the plane of 90 the end face of the head so that said cutters overlap with their cutting edges inclining downwardly from the end face of the head and means for adjustably securing said cutters in the head.

3. A bit comprising a head having an end face with a lead screw, a plurality of slots disposed tangentially of the lead screw in the end face of said head, said slots lying in planes inclined relative to that of the 100 face of the head and cutters having shanks slideable in said slots, said slots of such angularity and said cutters of such thickness to admit of the overlapping of said cutters when a greater number than two cutters are 105 used on said head.

4. An expandible bit comprising a shank with a longitudinally split head, the latter having a central lead screw in its face and a transverse seat countersunk in the said 110 face tangentially to the lead screw, an adjustable cutter arranged in the seat with its cutting edge tangential to the screw and its width substantially perpendicular to the axis of the shank, the longitudinal axis of the 115 cutter lying at a slight angle to a plane perpendicular to the axis of the shank, the split of the head bisecting the seat in a line parallel to its length, and means passing through the opposed sections of the head 120 above the cutter head for closing the seat walls on an inserted cutter.

5. An expandible bit comprising a shank with an enlarged head portion having a lead screw co-axial with the shank, transversely 125 disposed slots or seats disposed transversely of the bit and angularly as to each other undercut in the end face of the head, one of the side-walls of each of the seats being substantially tangential to the lead screw, said 130

- head being longitudinally slotted inwardly from the bottom of each slot in a plane parallel with the length of each slot to form relatively movable jaws on each side of each 5 slot, cutter blades adapted to be inserted in the slots to extend with their cutting edges tangentially to the lead screw and their width lying substantially flat across the end face of the head and the lengths of the cutters being slightly inclined with relation to a plane perpendicular to the axis of the shank, and means passing through coordinate portions of the split head for clamping the same onto said inserted cutters.
- 10 6. An expandible bit comprising a shank, and having a head with a substantially plane end face and a lead screw co-axial with the axis and projecting from said face, the end face provided with a plurality of 15 angularly disposed undercut slots with their widths substantially perpendicular to the axis of the lead screw and their lengths arranged secantially across the head, the head being slotted longitudinally inwardly from 20 the bottom of the slots so that the side walls thereof form relatively lateral, movable, clamping jaws, complementary cutters constructed and arranged to be fitted in said slots between the jaws, and to be disposed 25 with their cutting edges tangentially to the lead screw, and their bodies lying with their widths substantially flat across the end face, and means for clamping the respective jaws 30 of the head onto an inserted cutter.
- 35 7. An expandible bit comprising a shank with a longitudinally split head, the latter having a lead screw in its end face coaxial with the shank and a transverse seat counter-sunk in the said face substantially tangential to the lead screw, the head being 40 longitudinally split between the side walls
- of said seat whereby to form a pair of relatively movable cutter clamping faces; and an adjustable cutter arranged in the seat with its cutting edge substantially tangential to the screw and its width substantially perpendicular to the axis of the shank, the longitudinal axis of the cutter lying at a slight angle to a plane perpendicular to the axis of the shank, the split of the head dividing the seat lengthwise and means for tending to close the split and for clamping the cutter in the seat.
8. An adjustable bit having a cutter carrying head and a lead screw, a plurality of 45 transversely adjustable cutters having cutting edges extending from the lead screw, said cutting edges angularly disposed relative to the longitudinal axis of the head and at least two of the edges lying in vertical 50 planes which are at an angle to each other.
9. In an adjustable bit having a cutter carrying head and a lead screw a plurality of transversely adjustable cutters having cutting edges extending tangentially from 55 said lead screw, and angularly disposed relatively to the longitudinal axis of the head and at least two of the edges lying in vertical 60 planes which are at an angle to each other, said head being slotted adjacent and 65 above said cutters to form therewith shaving escarpment channels.
10. In an adjustable bit, a head having a flat end face and a plurality of slots in said end face to accommodate cutters, and channels extending upwardly through said head from adjacent slots to permit the escape of 70 chips.
- In testimony whereof they affix their signatures.
- JOHN CRAWFORD.
FREDERICK A. WEAVER.
